UNITED STATES PATENT OFFICE.

EDWARD LUTHER KRAFT, OF YORK, PENNSYLVANIA, ASSIGNOR TO ATLAS TRUCK CORPORATION, OF YORK, PENNSYLVANIA, A CORPORATION OF DELAWARE.

TROLLEY POLE FOR TRACKLESS TROLLEY CARS.

1,411,849.

Specification of Letters Patent.

Patented Apr. 4, 1922.

Application filed June 8, 1921. Serial No. 476,040.

To all whom it may concern:

Be it known that I, EDWARD LUTHER KRAFT, a citizen of the United States of America, and a resident of York, county of York, and State of Pennsylvania, have invented certain new and useful Improvements in Trolley Poles for Trackless Trolley Cars, of which the following is a full and clear specification.

10 This invention has relation to that class of trolley-poles especially adapted for cars or busses that operate without tracks, being free to be steered over a predetermined zone in the roadway without disconnecting the trolley from the overhead trolley-wire.

15 In the drawings—

Fig. 1 is a view partly in vertical section and partly in side elevation of my apparatus;

20 Figs. 2 and 3 are detail views hereinafter described.

Referring to the drawing, 5 designates a tube depending through the car structure and rigidly affixed thereto, preferably by 25 a top flange 6 resting on the foot-board on the top of the car and, by means of a pair of flanged nuts 7, screwed on the exterior of the tube 5 and adapted to clamp the roof 8 of the car structure.

30 Mounted to rotate on the tube 5 is a head 9 which is supported on the tube by suitable roller-bearings 10 surrounding the tube 11 which depends through the stationary tube 5, said tube 11 being rigidly 35 affixed to the head 9 so as to turn with it. To the head 9 is pivoted the trolley-pole 12, which, for the sake of lightness and flexibility, is desirably made of wood, preferably bamboo. A set of retractile springs

40 13 normally tend to throw the trolley-pole upwardly, as usual. Within the head 9 is mounted a pulley 14, and extending rearwardly and downwardly from the head 9 is a rigid tube 15 carrying at its forward

45 end a pulley 16, housed in a casing 17 screwed to the extreme end of said tube 15. A cable 18 has its free end connected to the trolley-pole and then extends down into the casing 17, around the pulley 16, into the

50 tube 15, over the pulley 14, and down through the tube 11, terminating within the car. Projecting forwardly from the tube 15 is a guard-rod 19 which prevents the cable 18 from becoming looped around the

55 forward end of the stationary tube 15 when-

ever the payed-out portion of the cable becomes loose enough to hang down far enough to loop around said forward end of the tube 15, which looseness occurs occasionally in the ordinary operation of the trolley. 60 The tube 15 is braced to the head 9 by means of a rigid stay-rod 20, thereby providing a light yet very rigid rotatable head-structure for the trolley-pole.

The end of the tube 11 depends to a point 65 below the lower end of the tube 5 and has screwed to it a casing 21 which encloses a pulley 22 affixed to a shaft 23. The cable 18 is wound upon the pulley 22 so that by turning the shaft 23 the cable may be 70 drawn-in to pull the trolley-pole down into non-use position, or payed-out to permit it to normally swing upwardly into operative position. The shaft 23 is manually rotated by means of a wheel 24 affixed to one end 75 of the shaft 23, and in order to keep the operator acquainted with the position of the trolley-pole at all times so that he will be able to avoid steering the vehicle far enough toward either side of the trolley 80 conductor to dislodge the trolley from the wire, I provide an arcuate indicating plate 25 on the stationary tube 5 and an arrow or pointer 26 on the rotatable casing 21. It will be understood that the casing 21, together with the pulley therein and the operating wheel 24, all rotate bodily with the rotatable tube 11, this rotatability being a 85 free one in order to permit the trolley-pole to follow the trolley-wire as the vehicle is 90 steered to one side or the other thereof. A second anti-friction bearing 27 is provided near the lower end of the tube 11 in order to maintain the same in upright position, and, in order to hold the drum 22 against 95 rotation when the trolley-pole is down, I provide a suitable ratchet device 28.

It will be observed that the drum 22 is narrow, having its cable-receiving groove only a little greater than the diameter of the cable, so that the cable is compelled to wind on the drum clock-spring-fashion, thereby avoiding as much as possible the rubbing of the cable against the lower end of the tube 11 as the cable is drawn-in or payed-out. 100

The numeral 29 designates an upstanding lug which is adapted to be struck by a lug 30 on the rotatable structure and thereby prevent this structure from making a complete rotation. 105

The nature and scope of the invention having been thus indicated and its preferred embodiment having been specifically described, what is claimed as new is:

- 5 1. A trolley-pole structure embodying a trolley-pole attached to a rotatable head, a bearing tube depending through the roof structure of the car and into the car interior and adapted to rotatably support said head, 10 a cable-tube attached to the head and depending through said stationary bearing tube, a bearing in said bearing-tube for the lower end of the cable-tube, a cable connected to the trolley-pole and extending down through said cable-tube, and means attached to the lower end of said cable-tube for paying-out and drawing-in the cable. 15
2. A trolley-pole structure embodying a trolley-pole attached to a rotatable head, a bearing tube depending through the roof structure of the car and into the car interior and adapted to rotatably support said head, a cable-tube attached to the head and depending through said stationary bearing tube, a bearing in said bearing-tube for the lower end of the cable-tube, a cable connected to the trolley-pole and extending down through said cable-tube, and means attached to the lower end of said cable-tube 20 for paying-out and drawing-in the cable, 25 said means being rotatable with the cable tube and embodying a pulley and an enclosing casing.
3. A trolley-pole structure embodying a trolley-pole attached to a rotatable head, a bearing tube depending through the roof structure of the car and into the car interior and adapted to rotatably support said head, a cable-tube attached to the head and depending through said stationary bearing tube, a bearing in said bearing-tube for the lower end of the cable-tube, a cable connected to the trolley-pole and extending down through said cable-tube, and means attached to the lower end of said cable-tube for paying-out and drawing-in the cable, said means 35 embodying an indicating-device showing within the car the position of the trolley-pole. 40
4. In a trolley-pole structure of the type set forth, a rotatable head carrying a spring-actuated trolley-pole, means for pulling down the trolley-pole embodying a tube rigidly extending rearwardly from said head and carrying a pulley at its rear end. 45
5. In a trolley-pole structure of the type set forth, a rotatable head carrying a spring-actuated trolley-pole, means for pulling down the trolley-pole embodying a tube rigidly extending rearwardly from said head and carrying a pulley at its rear end, said tube being provided with a rearwardly-extending guard-rod. 55

In testimony whereof I hereunto affix my signature.

EDWARD LUTHER KRAFT.
